INVENTOR
PRESTON E. GILLING

BY
A. D. J. Libby
ATTORNEY

UNITED STATES PATENT OFFICE.

PRESTON E. GILLING, OF EAST ORANGE, NEW JERSEY.

ELECTRICAL CONDENSER.

Application filed March 13, 1925. Serial No. 15,231.

- This invention relates to an electrical condenser in which a stack of alternate layers of mica and metal foil are built up in any satisfactory manner such as described in 5 Van Deventer Patent 1,181,623 issued May 2, 1916, or in the application of Harry A. Hatch, Serial No. 424,328 filed October 16, 1920, now Patent 1,574,424, issued Feb. 23, 1926.
- 10 In the patent and application just referred to, special clamps are used for holding the stack together, said clamps also acting as terminals to which electrical conductors may be connected.
- 15 My present invention is directed to an improved form of clamping means for the stack, which clamping means also utilizes one of the condenser elements of the stack.
- 20 A further object of my invention is to provide an improved arrangement of binding the condenser elements into a complete unit so that the condenser will hold its rated capacity over a long period of time.
- 25 Another object of my invention is to provide at least one pair of condenser element plates of such thickness that these plates may be utilized as the binding means, at the same time have formed thereon terminals to which electrical conductors may be 30 quickly attached.
- Other objects will appear from a study of the following specification taken in connection with the annexed drawing wherein—
- Figure 1 is a plan view of the condenser stack.
- Figure 2 is an enlarged side view of the stack shown in Fig. 1.
- Figure 3 is a top view of one of the outside condenser element plates.
- 40 Figure 4 is a bottom view of Fig. 3.
- Figure 5 is a top view of the other outside element plate.
- Figure 6 being a bottom view of Fig. 5.
- Figure 7 is a plan view of one of the binding members.
- 45 Figure 8 is a side elevation of the complete condenser showing a grid leak resistance unit mounted between the terminals of the condenser.
- 50 Figure 9 is an end view of Fig. 8.
- Figure 10 is a central longitudinal sectional view through the condenser without the grid leak.
- In the drawing wherein like numbers refer to corresponding parts in the various views, 1 is a stack made up of alternate layers of suitable di-electric, such as mica and metal foil. Alternate metal foils have their ends brought out beyond the end of the stack and are bent downward over the 55 end and bottom of the stack as indicated at 2, while at the other end of the stack, the alternate metal foils are brought out and bent over the end of the stack as indicated at 3. Contacting with the bent over ends 60 2 and 3 is a pair of conducting plates 4 and 5. The plate 4 is formed with a tongue 6 and a pair of fingers 7 and 8, the latter of which are bent so as to form eyelets 9 for the purpose of gripping a conductor or bus-bar which may be slid through said eyelets. The tongue 6 of the plate 4, before it is 65 formed to the position shown in Fig. 3, is first passed through a slot 10 in one of the binding members 11. The binding member 70 75 is preferably made of strong insulating material. A binding member 11 is on the bottom or on the outside of the plate 4 as indicated in Figs. 8 and 10. The conducting plate 5 is similar to 4, except the tongue 6 is formed in reversed direction as will be 80 seen in Figs. 5 and 6. A second binding member 11, exactly the same as the one used in connection with plate 4, is attached to the bottom of plate 5 by passing the tongue 6 85 thereof through the slot 12. After the binding members 11 have been assembled on the plates 4 and 5 through the medium of the tongues 6, the plates are applied to opposite sides of the stack 1 and the tongues 90 6 are bent downward into the slots 10 and 12 of the binding member 11. Each of the plates 4 and 5 are preferably provided with a clearance opening 13 larger than the openings 10 and 12 so that the tongues 6 will 95 not short circuit the plates 4 and 5. The plates 4 and 5 are made materially thicker than the foil plates comprising the stack 1 so as to have considerable stiffness themselves whereby the eyelets 9 may be formed 100

directly from these plates and also the plates may have extending terminals 14 and 15 respectively between which a grid leak or resistance element 16 may be mounted.

5 It is to be understood that the stack 1 may be of any desired thickness depending on the capacity required. For certain classes of work, for example, in radio circuits, relatively low capacity condensers are used and 10 stack 1 for this purpose will then be very thin, in fact, the condenser may be reduced in capacity in such a form as to consist of only the conducting plates 4 and 5 themselves without any intermediate stack or 15 condenser elements.

My condenser may be mounted in any satisfactory manner as for example, the bus-bars may support the condenser entirely by being passed through the eyelets 9. In 20 this case, the condenser can be slidably adjusted on a bus-bar to balance up the radio set all as described in my application Serial No. 10,214 filed February 19, 1925.

While I have described one form of my 25 invention it is apparent that the details may be varied without departing from the spirit of the invention or the scope of the appended claims.

Having thus described my invention what 30 I claim is:

1. An electrical condenser comprising a stack of the character described, having the protruding ends of one group of foils bent over the end of the stack in one direction 35 and the ends of the other group bent over the other end of the stack in an opposite direction, a condenser element plate on each side of the stack engaging respectively said bent over foil ends, a pair of binding members over said plates, portions of said plates acting as fastening means to draw and clamp the binding members against the stack and terminal connecting means on 40 said plates.

45 2. An electrical condenser comprising a stack of the character described, having the protruding ends of one group of foils bent over the end of the stack in one direction and the ends of the other group bent over the other end of the stack in an opposite direction, a condenser element plate on each side of the stack engaging respectively said bent over foil ends, a pair of insulating binding members over said plates, a portion 50 of one plate engaging the same ends of both binding members while a portion of the other plate engages the other ends of both binding members, to clamp said members onto the stack and terminal connecting 55 means on said plates.

60 3. An electrical condenser comprising a stack of the character described, having the protruding ends of one group of foils bent over the end of the stack in one direction and the ends of the other group bent over 65

the other end of the stack in an opposite direction, a condenser element plate on each side of the stack engaging respectively said bent over foil ends, a pair of insulating binding members over said plates, a portion 70 of one plate passing through an opening in the end of one binding member and over the end of the other binding member while a portion of the other plate is similarly disposed with respect to the other ends of said 75 binding members and terminal connecting means on said plates.

4. An electrical condenser comprising a stack of the character described, having the protruding ends of one group of foils bent 80 over the end of the stack in one direction and the ends of the other group bent over the other end of the stack in an opposite direction, a pair of condenser element plates, lying over said stack and having gripping tongues formed thereon but in opposite directions, a pair of binding members of insulating material each having slots 85 therein at opposite ends to receive said tongues as described so as to bind said members securely to the stack, said plates each being provided with at least one circuit connecting means.

5. An electrical condenser comprising a stack of the character described, having the protruding ends of one group of foils bent 90 over the end of the stack in one direction and the ends of the other group bent over the other end of the stack in an opposite direction, a pair of condenser element plates 95 lying over said stack and having gripping tongues formed thereon but in opposite directions, a pair of binding members of insulating material each having slots therein 100 at opposite ends to receive said tongues as described, one tongue passing all the way through one of the slots in one of said members and then being bent over the end of the stack and the end of said second member 105 into the slot in that end while the tongue on the other plate passes all the way through the remaining slot in the said second member and being bent over the opposite end of the stack into the remaining slot in the first mentioned member thereby clamping the 110 member securely to the stack, said plates each having at least one circuit connecting means provided thereon.

6. An electrical condenser comprising a stack having a plurality of thin conducting plates separated by thin di-electric plates, a pair of conducting plates much thicker than said thin plates, on the outer sides of the stack, said conducting plates acting as condenser elements and joined with said 120 thin conducting plates, if any, to make up the stack, an insulating binding member outside each of said thicker conducting plates, means on said thicker plates for clamping said binding members against 125 130

themselves and the stack and at least one circuit connecting means provided on each of said thicker plates.

7. An electrical condenser having at least 5 a pair of conducting plates of relatively good stiffness, said conducting plates acting as condenser elements and joined with said thin conducting plates, if any, to make up the stack, an insulating binding member

outside each of said plates, means preferably integral with each of said plates for clamping said binding members against themselves and at least one circuit connecting means provided on each of said plates.

In testimony whereof, I affix my signature.

PRESTON E. GILLING.
